UNITED STATES PATENT OFFICE.

LLOYD L. MELTON, OF CHICAGO, ILLINOIS.

INTERNAL-COMBUSTION ENGINE.

1,378,260.

Specification of Letters Patent. Patented May 17, 1921.

Application filed August 21, 1919, Serial No. 318,938. Renewed October 6, 1920. Serial No. 415,216.

To all whom it may concern:

Be it known that I, LLOYD L. MELTON, citizen of the United States, residing at Chicago, in the county of Cook and State of Illinois, have invented a certain new and useful Improvement in Internal-Combustion Engines, of which the following is a full, clear, concise, and exact description.

My invention relates to internal combustion hydrocarbon engines which employ electric spark plugs for exploding the charges admitted to the engines and has for its object the provision of improved means for including the spark plugs in circuit. The structure of my invention renders the wiring of the spark plugs water and dust proof and maintains the conducting wires in fixed position, a further advantage being that short circuiting is avoided not only by the action of water and other foreign matter but also by the elimination of any looseness in the wiring.

My invention may be embodied in an engine having a single cylinder but it is especially useful in conjunction with a plural cylinder engine. In carrying out my invention I employ a hood at the spark plug end of the engine, this hood containing connections that lead to the spark plugs and carrying a mounting for some of these connections which are extended through or along the mounting to the engine exterior where they have switching connection with wires that extend to the source of current by way of a timer, in the case of a plural cylinder engine but to which the invention is not to be limited.

The wires that extend to the timer are embedded in a body of insulation which is preferably molded about the same so as to maintain the wires in fixed relation with each other as well as with such body of insulation.

I will explain my invention more fully by reference to the accompanying drawing showing the preferred embodiment thereof and in which Figure 1 is an end view of an engine having a number of cylinders, a part of the structure shown being illustrated in cross section; Fig. 2 is a plan view of the cover portion of the engine that contains current conducting devices for including the spark plugs of the various cylinders in circuit; Fig. 3 is a detail view on a large scale of a part of the structure appearing in Fig. 1 but showing a separation between

the embedded wires extended from the timer and the connections extending into the interior of the hood; and Fig. 4 is a view on line 4—4 of Fig. 1 with a section broken away because of lack of space.

Like parts are indicated by similar characters of reference throughout the different figures.

The internal combustion engine illustrated may be of any suitable type whose charges are ignited by electrically produced sparks, Fig. 1 showing one cylinder 1 of such an engine partly broken away. This cylinder has a head 2 provided with a conical recess 3 within which the spark plug 4, of any suitable design, is disposed. The inner end of the spark plug is provided with two separated contacts that constitute the sparking gap. Each of the other cylinders of the engine is similarly equipped, all as is well understood by those skilled in the art.

A water and dust tight hood 5 has tight engagement with the top of the engine, this hood extending across the entire engine structure so as to overlie all the spark plugs 4 thereof to protect the same from water, dust, and other foreign matter. A board 6 of insulation such as fiber or vulcanite is bolted against the under side of the lugs or ribs 7 that are provided within the hood 5. This board has an angular extension, as illustrated clearly in Fig. 2, this angular extension extending through an opening in the hood, the margins of the opening being so closely engaged by the board as to render the hood water and dust proof at this place where the board passes therethrough. The skirt of the hood has water and dust proof engagement with the top of the engine, there being desirably means whereby the hood is latched down upon the engine by the latching structure 8 at one end of the engine, the hood being desirably adapted for pivotal or hinged connection with the other end of the engine, as indicated at 9. The hinge 9 is desirably in the nature of an inturned lip, formed upon the hood, that is snugly received in a corresponding groove in the engine, this hinge structure being therefore of such a nature that after the hood is released at the latch 8 it may not only be raised but may be bodily removed.

In the preferred embodiment of the invention there are desirably as many guides 10 as there are spark plugs, these guides being mounted upon the bottom face of the

board 6. These guides have bores which are axially alined with the spark plugs and in which the longitudinally movable metallic conducting pins 11 are movable longitudinally of the spark plug. These pins have abutting engagement with the outer ends of the metallic current conducting posts 12 which carry sparking contacts which are complemental to other sparking contacts 10 that are grounded upon the engine as is understood.

A mounting block 13 is mounted upon the upper side of the board 6 and carries current conducting contact springs 14, one for each pin 11. These springs exert downward pressure upon the pins 11 in the direction of their movability and maintain the lower or inner ends of these pins in firm electrical connection with the posts 12. The springs 15 20 are connected with metallic plug receiving socket 15, there being one such socket for each spring and therefore one for each spark plug. The sockets of the various springs are desirably assembled upon the angular extension 16 of the board 6 at the front end of the engine. Each socket is connected with its spring by means of a metallic strip or wire 17 mechanically and electrically connected with its socket 15 at one end and provided 25 at its other end with a threaded socket 18 which receives a threaded stem of the screw 19 whose head is screwed firmly down upon the corresponding spring 14. The entire arrangement is such that each spring is effectively electrically connected with its socket 15 by a structure whose parts are in mechanically fixed relation. The screws 19 may also be relied upon to hold the block 13 down upon the board 6 to maintain these 30 parts 13 and 6 in fixed relation.

The portions 16 of the board snugly engage the margins of the opening in the hood 5 through which this board portion projects but I desirably further guard the opening 45 in the hood 5 through which the board is extended by means of a canopy 20. The sockets 15 desirably face downwardly and are preferably placed in a straight row which is upon the exterior of the engine to 50 be in position to be slipped into engagement with the split spring plugs 21 in which the wires 22 terminate, these plugs being embedded at their inner ends within a body of insulating material 23 in which the wires 55 22 are preferably molded. This body of insulating material 23 is secured to the exterior side of the engine by screws 24 which serve to position the plugs 21 so that they may readily be engaged by the sockets 15 when 60 the hood is placed in closed position to be held in such position at its forward end by the latch 8. Thus, as the hood is swung closed upon its hinge 9 the springs 14 and the spark plugs individual thereto will be 65 brought into connection with the wires 22

pertaining thereto and when the hood is opened the connections between said wires and springs are broken. Where the engine employs a plurality of cylinders the lower end of the insulating body 23 may constitute the cap 25 of the casing of a timer 26, the lower ends of the wires 22 terminating in contacts 27 that are within the interior of the timer casing to be successively engaged by the wiper 28 which is operated by the well known gearing 29 driven by the engine. The cap 25 is snugly engaged with the body of the timer casing so that the structure is weather proof at this point as well as elsewhere. 75 80

While I have herein shown and particularly described the preferred embodiment of the invention I do not wish to be limited to the precise details of construction shown as changes may readily be made without departing from the spirit of my invention, but having thus described my invention I claim as new and desire to secure by Letters Patent the following:—

1. An internal combustion engine having 90 a plurality of cylinders each provided with a spark plug, in combination with a hood; current conducting means within the hood for including the spark plugs in circuit; a mounting for the current conducting means 95 which extends through an opening provided in the hood; switching parts, one for each engine cylinder, carried by said mounting upon the exterior of the hood and connected with the aforesaid current conducting 100 means; conductors upon the exterior of the engine, one individual to each engine cylinder, for connecting the spark plug thereof with a source of current and terminating, adjacent the aforesaid switching parts, in 105 other switching parts, the first aforesaid switching parts being disposed to be engageable by the closure of the hood with the second aforesaid switching parts; a timer provided with a casing having a cap portion 110 at which the conductors upon the exterior of the engine terminates in timer contacts; and a body of insulating material connected with said cap portion and holding said conductors and the switching parts in 115 which these conductors terminate in substantially fixed relation.

2. An internal combustion engine having a plurality of cylinders each provided with a spark plug, in combination with a hood; current conducting means within the hood for including the spark plugs in circuit; switching parts one for each engine cylinder, carried by the hood upon its exterior and connected with the aforesaid current 120 conducting means; conductors upon the exterior of the engine, one individual to each engine cylinder, for connecting the spark plug with a source of current and terminating, adjacent the aforesaid switching parts, 125 130

- in other switching parts that are complementary to the aforesaid switching parts, the first aforesaid switching parts being engageable with the second aforesaid switching parts; a timer provided with a casing having a cap portion at which the conductors upon the exterior of the engine terminate in timer contacts; and a body of insulating material connected with said cap portion and holding said conductors and the switching parts in which these conductors terminate in substantially fixed relation. 5
3. An internal combustion engine having a plurality of cylinders each provided with a spark plug, in combination with a hood; current conducting means within the hood for including the spark plugs in circuit; a mounting for the current conducting means which extends through an opening provided in the hood; switching parts, one for each engine cylinder, carried by said mounting upon the exterior of the hood and connected with the aforesaid current conducting means; conductors upon the exterior of the engine, one individual to each engine cylinder, for connecting the spark plug thereof with a source of current and terminating, adjacent the aforesaid switching parts, in other switching parts, the first aforesaid switching parts being disposed to be engageable by the closure of the hood with the second aforesaid switching parts; and a timer provided with a casing having a cap portion at which the conductors upon the exterior of the engine terminate in timer contacts. 10
4. An internal combustion engine having a plurality of cylinders each provided with a spark plug, in combination with a hood; current conducting means within the hood for including the spark plugs in circuit; switching parts, one for each engine cylinder, carried by the hood upon its exterior and connected with the aforesaid current conducting means; conductors upon the exterior of the engine, one individual to each engine cylinder, for connecting the spark plug with a source of current and terminating, adjacent the aforesaid switching parts, in other switching parts that are complementary to the aforesaid switching parts, the first aforesaid switching parts being engageable with the second aforesaid switching parts; and a timer provided with a casing having a cap portion at which the conductors upon the exterior of the engine terminate in timer contacts. 15
5. An internal combustion engine provided with a spark plug, in combination with a hood; current conducting means within the hood for including the spark plug in circuit; a switching part carried by the hood upon its exterior and connected with the aforesaid current conducting means; and a conductor upon the exterior of the engine for connecting the spark plug with a source of current and terminating, adjacent the aforesaid switching part, in another switching part that is complementary to the aforesaid switching part, these switching parts being engageable by the closure of the hood. 20
6. An internal combustion engine provided with a spark plug, in combination with a hood; current conducting means within the hood for including the spark plug in circuit; a mounting for the current conducting means which extends through an opening provided in the hood; a switching part carried by said mounting upon the exterior of the hood and connected with the aforesaid current conducting means; and a conductor upon the exterior of the engine for connecting the spark plug with a source of current and terminating, adjacent the aforesaid switching part, in another switching part that is complementary to the aforesaid switching part, these switching parts being engageable by the closure of the hood. 25
7. An internal combustion engine provided with a spark plug, in combination with a hood; a current conducting pin for connecting a terminal of the spark plug in circuit; a spring maintaining said pin in circuit; a switching part carried by the hood upon its exterior and connected with said spring; and a conductor upon the exterior of the engine for connecting the spark plug with a source of current and terminating, adjacent the aforesaid switching part, in another switching part that is complementary to the aforesaid switching part, these switching parts being disposed to be engageable by the closure of the hood. 30
8. An internal combustion engine provided with a spark plug, in combination with a hood; a current conducting pin for connecting a terminal of the spark plug in circuit; a spring maintaining said pin in circuit; a mounting for said spring through which said pin is free to move; a switching part carried by the hood upon its exterior and connected with said spring; and a conductor upon the exterior of the engine for connecting the spark plug with a source of current and terminating, adjacent the aforesaid switching part, in another switching part that is complementary to the aforesaid switching part, these switching parts being engageable by the closure of the hood. 35
9. An internal combustion engine provided with a spark plug, in combination with a hood; current conducting means within the hood for including the spark plug in circuit; a switching part carried by the hood upon its exterior and connected with the aforesaid current conducting means; and a conductor upon the exterior of the engine for connecting the spark plug with a source of current and terminating, adjacent the aforesaid switching part, in another switching part that is complementary to the aforesaid switching part, these switching parts being engageable by the closure of the hood. 40
10. An internal combustion engine provided with a spark plug, in combination with a hood; current conducting means within the hood for including the spark plug in circuit; a switching part carried by the hood upon its exterior and connected with the aforesaid current conducting means; and a conductor upon the exterior of the engine for connecting the spark plug with a source of current and terminating, adjacent the aforesaid switching part, in another switching part that is complementary to the aforesaid switching part, these switching parts being engageable by the closure of the hood. 45
11. An internal combustion engine provided with a spark plug, in combination with a hood; current conducting means within the hood for including the spark plug in circuit; a switching part carried by the hood upon its exterior and connected with the aforesaid current conducting means; and a conductor upon the exterior of the engine for connecting the spark plug with a source of current and terminating, adjacent the aforesaid switching part, in another switching part that is complementary to the aforesaid switching part, these switching parts being engageable by the closure of the hood. 50
12. An internal combustion engine provided with a spark plug, in combination with a hood; current conducting means within the hood for including the spark plug in circuit; a switching part carried by the hood upon its exterior and connected with the aforesaid current conducting means; and a conductor upon the exterior of the engine for connecting the spark plug with a source of current and terminating, adjacent the aforesaid switching part, in another switching part that is complementary to the aforesaid switching part, these switching parts being engageable by the closure of the hood. 55
13. An internal combustion engine provided with a spark plug, in combination with a hood; current conducting means within the hood for including the spark plug in circuit; a switching part carried by the hood upon its exterior and connected with the aforesaid current conducting means; and a conductor upon the exterior of the engine for connecting the spark plug with a source of current and terminating, adjacent the aforesaid switching part, in another switching part that is complementary to the aforesaid switching part, these switching parts being engageable by the closure of the hood. 60

In witness whereof I hereunto subscribe my name this 14th day of July, A. D. 1919. 125

LLOYD L. MELTON.
